ELECTRICAL SIGNALLING SYSTEM
WITH REMOTE CONTROL

Willy Pouliart, Antwerp, Belgium, assignor to International Standard Electric Corporation, New York, N. Y., a corporation of Delaware

Application January 22, 1943, Serial No. 473,276
In the Netherlands June 23, 1941

11 Claims. (Cl. 179—85)

1

This invention relates to new and useful improvements in electrical signaling systems and particularly in systems for supervising and/or controlling from a central point the positions of a plurality of mechanisms located at one or more distant points by means of electrical signals sent over a small number of wires.

Many such signaling systems are known in which indications are sent from the outlying point to the central point, or in which means are provided for actuating mechanical or electrical devices at a distant point by manipulations at the central point. These known systems operate on one of the following two principles:

(a) *Code systems*

Each mechanism at the distant end is provided with one or more contact sets, each set corresponding to a definite position or condition which it is desired to indicate. To each contact set is assigned a predetermined code, consisting of a combination of electrical current impulses. These impulses may consist of the opening and closing of a unidirectional direct current circuit, or of trains of impulses of positive or negative polarity.

The code sending device may be directly associated with each contact set and may be individual to each contact set, the code being released by a so-called "trigger" action, when the contacts are actuated. The code sending device may also be common to a plurality of contact sets, and the common code sender controlled by means individual to each contact set.

The different codes are received at the central point by an appropriate controlling device, which counts the number of pulses of different characteristics for the purpose of identifying each individual code.

Systems with individual code sending devices must, however, necessarily be provided with complicated mechanisms, which may impair the reliability of the operation.

Systems with a common code sender must be specially designed to avoid interfering reciprocal action between different indications. A further disadvantage is that during one revolution of the sender only one code can be sent.

(b) *Synchronized stepping systems*

These systems make use of a rotating mechanism, usually in the form of some type of selector switch with a bank of terminals and a rotating brush member at each end of the signaling wire. The arrangement is usually such that each con-

2

tact set, the position of which has to be indicated, is connected to a definite bank terminal at the distant point, whereas the relevant signal is connected to the corresponding bank terminal at the central point.

The two rotating mechanisms are arranged to rotate or step in synchronism, by means of any one of a plurality of known methods. During one revolution of the brush member the position of each contact set at the distant point is signaled to the central point by means of a ground, the absence of ground, a positive or negative battery, or any combination of such indications applied to the signaling wires.

15 The principal difficulty in the design of such systems lies in the provision of a temporary starting indication, which starts the rotating mechanisms whenever a contact set changes its position.

20 The temporary starting indication may be given by means of an extra spring or segment on the contact set, e. g., of power station circuit breakers, the movable armature of the contact set making temporary contact with the extra spring whenever the contact set changes its position.

25 All such means are, however, of a mechanical nature and cannot be used to signal the position of mechanisms which lack said extra spring or segment. Most of the existing systems designed on this basis are, therefore, very limited in their application.

The new signaling system according to this invention is of the synchronized stepping type.

30 The system requires two metallic signaling wires between the distant and the central points. No earth return connection is employed. The synchronization is achieved by very simple means, comprising ordinary telephone relays in a straight direct current circuit.

35 The main difference between the new signaling system and known systems is in the method of giving the temporary starting indication for the rotating mechanisms.

40 One feature of the invention provides for the giving of this indication in the form of a transient electrical surge in the secondary winding of a common transformer. This makes it possible to apply the new signaling system to any type of new or existing signaling installation, even if each contact set comprises only two springs, i. e., one make or one break contact, which is the smallest practicable contact set spring combination.

45 According to another feature of the invention

a cold-cathode tube is provided for the purpose of receiving and registering the temporary surge indication.

In my new signaling system it is also possible to establish a telephonic connection between the control and the distant points over the signaling wires without interfering with the signal transmission proper.

The manner in which the new signaling system functions will now be described with the aid of the drawings, in which Fig. 1 is a diagram of the connections at the distant end, while Fig. 2 represents the connections at the central or supervisory point, only so much being shown as is necessary for a clear understanding of the invention.

In Fig. 1, IC designates one of a plurality of contact sets, which can be closed or open. The contact set is shown open.

Each contact set is provided with an individual resistance r_1 . One side of all these resistances is multiplied and connected in common to the primary winding of transformer T_1 ; the secondary winding of this transformer is connected to a potentiometer P, and also to the control electrode e_2 of a cold-cathode tube L.

The cold-cathode tube is of the well-known type, which requires a specific control gap breakdown potential V_x to light or ionize the control gap between the two electrodes e_1 and e_2 , and a much higher main gap breakdown potential V_y to light the main gap between the anode A and either of the two electrodes e_1 and e_2 . Once the control gap has been ionized, a potential V_z , which is considerably lower than V_y , is sufficient to maintain a current in the main gap.

The control electrode e_1 is permanently connected to the negative side of battery, while the control electrode e_2 (usually referred to as the control anode) is connected to a biasing potential on the potentiometer in series with the secondary winding of transformer T_1 . The biasing potential, which is applied in order to increase the sensitivity of the arrangement, is considerably lower than the control gap breakdown voltage, so that normally the tube will not be operated. An electrical surge produced in the secondary winding of transformer T_1 will be sufficient to increase the potential difference between e_2 and e_1 or between e_2 and A to a value, which is equal to or higher than the control gap breakdown voltage, or the main gap breakdown voltage.

The action of the electrical surge effect may be explained in the following manner:

Let it first be assumed that the contact of a contact set IC opens. By removing the ground from the corresponding resistance r_1 , the potential of the common point "O" is suddenly increased, thus causing a temporary change of the value of the current flowing through the primary winding of T_1 . This change will take place in a direction indicated by an arrow drawn in full lines and will induce a surge in the secondary winding of T_1 in a direction such that the potential of e_2 will be increased with respect to the potential e_1 . By a proper choice of the bias and of the dimensioning of transformer T_1 , this surge may be made to ionize the control gap.

Let it further be assumed that thereafter the contact set IC closes. By adding a resistance in the circuit the potential of the common point "O" will be suddenly lowered, causing also a temporary change in the value of the current flowing through the primary winding of T_1 . This change will take place in a direction indicated by an

arrow drawn in dotted lines and will induce a surge in the secondary winding of T_1 in a direction such that the potential of e_2 will be decreased with respect to the potential of the anode A. By proper design this surge may be made sufficient to break down the main gap directly.

It is obvious that the number of contact sets that can be connected in parallel to one transformer is limited only by practical considerations.

It is quite possible, however, to connect several transformers to one cold-cathode tube, e. g. by connecting the secondary windings in series, as indicated in dotted lines in Fig. 1, where a second transformer T_2 is shown.

The anode of the cold-cathode tube is connected via the winding of a relay S_1 to the positive pole of the battery.

SS_1 designates the power magnet of a step-by-step selector switch of the well-known type used in telephone or similar systems. This switch is provided with a bank of terminals, of which three levels, viz. a_1 , b_1 and c_1 with corresponding brush members x_1 , y_1 and z_1 are indicated. It should, however, be understood that the invention is not limited to the use of any particular type of selector switch, but that any other types of single or two-motion selector switches may be employed without changing or modifying the principle of the invention.

Each contact set is connected also individually to an individual terminal in the selector switch bank.

The selector switch is further provided with a spark quencher Q, interrupter contact Int_1 and an off-normal contact ONC_1 . The latter closes its lower spring set when the switch is in normal position, and opens it when the switch is in any other position.

Fig. 1 shows further a group of controlling relays, the function of which will be explained later.

Key K_{11} simulates a contact set and is provided for test purposes.

The telephone set TA_1 shown on the right-hand side of the drawing may be any type of common battery set connected to the two signaling wires w_1 and w_2 by means of two coupling condensers C_{12} . The telephone set is fed over a retardation coil M_1 .

Key K_{12} is the telephone call key, and the purpose of it is to ring the bell at the central point as long as the key remains depressed.

In Fig. 2, SS_2 designates the power magnet of a step-by-step selector switch of the same type as the one in Fig. 1. The switch has three banks of terminals a_2 , b_2 , c_2 and corresponding brush members x_2 , y_2 and z_2 . The switch is provided with a spark quencher Q_2 , an interrupter contact Int_2 and an off-normal contact ONC_2 . The latter closes its top spring set as long as the switch remains off-normal.

Each set of terminals in the banks a_2 and b_2 is connected to a pair of mechanically interlocking relays IR_1 and IR_2 . Each pair of such relays corresponds to one contact set (IC in Fig. 1). The interlocking relays are so designed that the operation of IR_1 will cause the closure of the left-hand contact, while the operation of IR_2 will close the right contact. When either relay is operated and closes its contact, the current may be removed from the winding of the relay without influencing the position of the armature.

Each pair of interlocking relays is associated with a pair of indicating lamps IL_1 and IL_2 , located on a control panel. These lamps are connected to give the following indications. Con-

tact IC open: lamp IL_2 lights; contact IC closed: lamp IL_1 lights.

Fig. 2 also shows a group of controlling relays, which will be later described.

A telephone set TA_2 is connected in the same manner as set TA_1 in Fig. 1.

Key K_{22} is the telephone call key, and functions in the same manner as K_{12} in Fig. 1.

Key CK is the central point checking key, which will also be described later.

Starting of indicating mechanism

Let it be assumed that the signal system is at rest and that both selector switches are in normal position.

Let it further be assumed that one of the indicator contacts opens. At that moment one resistance r_1 is disconnected from ground, and this will produce as previously explained an electrical surge in the secondary winding of transformer T_1 , with the result that the breakdown voltage of the control gap is attained. The control gap, and subsequently also the main gap, will be ionized, and relay S_1 will become energized. Relay S_1 operates also via the off-normal contact ONC_1 and the front contact of S_1 , after which relay S_1 locks itself over its own front contact. The operation of S_1 opens the anode circuit of the tube and since by this time the effect of the surge will have disappeared, the tube will become extinguished.

Relay H_1 will become energized in the circuit via interrupter contact Int_1 , brush X_1 and home terminal, front contact of relay S_1 , to ground. When relay H_1 closes its front contact, relay N_1 will operate in parallel with H_1 . Relay N_1 energizes the power magnet SS_1 and operates relay B_1 which connects battery to wire w_2 and ground to w_1 over the front contacts of relay F_1 and retardation coil D_1 .

Relay E_1 became energized in parallel with relay S_1 , thereby operating relay F_1 , which reversed the battery and ground connections to the signaling wire, for a purpose which will be explained later.

The battery connected to wire w_2 will cause the operation of relay A_{22} at the control station (Fig. 2) but relay A_{21} will not become energized, because it is shunted at that moment by rectifier R_{21} . Relay A_{22} in turn operates relay F_2 , which closes the energizing circuit for the power magnet of switch SS_2 .

When switch SS_1 (Fig. 1) attracts its armature, it opens the circuit for relays H_1 and N_1 . These relays are, however, made slow-releasing, so that sufficient time remains to check and transmit the indication in a manner to be described later.

When finally relay N_1 opens its front contacts, switch SS_1 will complete its first step. Relay B_1 releases whereupon the relays A_{22} and F_2 are also released (Fig. 2). Switch SS_2 will, therefore, also complete its first step.

As soon as the brushes of SS_1 leave their normal position, contact ONC_1 will open and relays ST_1 and E_1 release.

When the interrupter contact Int_1 closes after the first step, relay H_1 and subsequently relay N_1 will operate from the ground at the terminals a_1 of SS_1 . The cycle of operations above described will be repeated, with the result that the two selector switches will be driven in synchronism, step-by-step, until switch SS_1 comes to rest on the home position terminals after one complete

revolution. In this position the ground connection to relay H_1 is removed and both switches, therefore, stop rotating.

Let it now be assumed that one of the indicator contacts closes. In this case, as has already been explained above, the electrical surge in the secondary winding of T_1 will cause the breakdown of the main gap of the tube, after which the operation of the circuit continues as above described.

Transmission of contact set positions

Every time switch SS_1 stops on a set of bank terminals, to which an indication contact set is connected, a check is made over level b_1 to determine, whether the contact set is open or closed. If the contact is closed, there will be a ground on the b_1 level terminal, and if the contact is open, there will be no such ground.

If a ground is present, relay E_1 will operate over the brush y_1 , causing in turn the operation of relay F_1 , which will connect battery to wire w_2 and ground to w_1 .

If there is no ground, the relays E_1 and F_1 will not energize, so that battery is connected to wire w_1 and ground to wire w_2 .

In the control station the corresponding check for battery and ground is performed by relays A_{21} and A_{22} , which are shunted by two rectifiers R_{21} and R_{22} in such a way that A_{22} operates only with battery on wire w_2 while relay A_{21} operates only with battery on wire w_1 . The relays A_{21} and A_{22} energize locally relays E_2 and F_2 , respectively, and either one of these relays advances the brushes of switch SS_2 in synchronism with those of SS_1 , once the home position has been left.

The arrangement is such that the first starting pulse is always given in the form of a battery on wire w_2 , which causes the relays A_{22} and F_2 to operate. As soon as the brushes of SS_2 leave the home position, relay G_2 operates, after which the left front contacts of relays E_2 and F_2 are connected in parallel, until the brushes have completed their revolution.

Depending whether relay E_2 or relay F_2 has been operated, a ground is connected to relays IR_2 or IR_1 via brushes x_2 or y_2 . This ground energizes temporarily one of the indicating relays, which locks mechanically and lights the corresponding indicating lamp.

The following table gives the relationship between the contact set position and the operation of the various apparatus involved. A "+" sign indicates that a relay is energized, or a lamp lit, while a "-" sign indicates that a relay is de-energized or a lamp extinguished.

	IC closed	IC open
E_1	+	-
F_1	+	-
wire w_1	(1)	(2)
wire w_2	(2)	(1)
A_{21}	-	+
A_{22}	+	-
E_2	+	-
F_2	-	+
IR_1	+	-
IR_2	-	+
IL_1	+	-
IL_2	-	+

¹ Ground.

² Battery.

Remote control from central point

In any remote signaling system it must be possible for the central point supervisor to check at any moment the correctness of his lamp indica-

tions. For this purpose it is necessary and sufficient to provide the supervisor with means to start the selector switch at the distant point by a simple manoeuvre at the central point.

According to the invention this verification is performed as follows:

As soon as the supervisor depresses the check key CK in Fig. 2, relays D₂ and B₂ energize and connect battery to wire w₁ and ground to wire w₂. This causes the operation at the distant point of relay A₁₁, while relay A₁₂ cannot operate due to the shunting effect of rectifier R₁₂. Relay A₁₁ in turn operates relay G₁.

When the supervisor releases key CK, relays D₂, B₂, A₁₁ and G₁ are de-energized, but relay G₁ releases more slowly than relay A₁₁, so that the ground at the back contact of relay A₁₁ will be on long enough to energize relay S_{t1}, which locks. Relay E₁ energizes in parallel with S_{t1}.

The operation of relay S_{t1} starts the advancement of the selector switches as explained above, and during the full revolution of the brushes the positions of all the contact sets are checked.

As soon as switch S_{S2} leaves the normal position, the check lamp CL lights as an indication that the starting operation has been successful.

In the preceding description the relays A₁₁, A₁₂, A₂₁ and A₂₂ were described as functioning on an electrical current of a predetermined direction by means of a properly poled rectifier or other non-linear resistance connected in parallel to each relay. It is evident that the same result could be obtained by using ordinary polarized relays of any suitable design, the relays A₁₁ and A₁₂ and A₂₁ and A₂₂, respectively, being polarized in opposite directions.

Telephone call

If a person at the distant point desires to establish a telephone communication with the central point, he removes the receiver and temporarily depresses the telephone call button K₁₂, thereby operating relay B₁. This relay connects battery to wire w₁ and ground to wire w₂, resulting in the operation of relay A₂₁ at the central point. The latter in turn operates relay E₂, which closes the circuit for a direct current bell, a regular telephone drop or any other suitable signaling device. The bell will ring, as long as key K₁₂ remains depressed.

The supervisor removes the receiver, whereupon the conversation may take place. If the supervisor at the control station desires to call the distant point, he removes the receiver and depresses the telephone call key K₂₂, thereby operating relay B₂. This relay connects battery to wire w₂ and ground to wire w₁, resulting in the operation of relay A₁₂ at the distant point. The latter closes the circuit for a bell, a drop or any other suitable signaling device. The bell will ring as long as key K₂₂ remains depressed.

When the person at the distant point removes the receiver, conversation may take place.

It is obvious that the telephone conversation once established, is carried on without interfering with the signaling.

The supervisor at the control station should, however, not originate a telephone call while the check lamp is burning, because that might influence the correct receipt of the signals.

The person at the distant end can only originate a call, while switch S_{S1} is in normal position. If key K₁₂ is depressed, while the brushes of the switch are rotating, this has no effect.

Testing facility

The person at the distant end can verify that the equipment starts out correctly by depressing the test key K₁₁. By doing so he connects a resistance r₄ in parallel to the resistance r₁ and this has the same effect as if the contact set had been closed.

Alarms

16 It may happen that for some unforeseen reason the two selector switches fall out of synchronism with the result that switch S_{S2} may be left standing in some off-normal position. It has already been mentioned that relay G₂ in Fig. 2 remains operated during the whole time that switch S_{S2} is out of its normal position. Relay G₂ in turn energizes relay H₂, which is now locked over its own front contact. Relay H₂ also closes the energizing circuit for a thermostatic relay TE, but this relay has not sufficient time to leave its back contact during one revolution of S_{S2}.

If, however, for some reason the brushes of S_{S2} are prevented from returning to normal within a predetermined lapse of time, the thermostatic relay will function, resulting in the operation of 25 the alarm relay N₂ via front contacts of the relays H₂, TE and G₂. Relay N₂ locks to a back contact of key CK and closes the contacts for actuating an appropriate alarm signal. Relay N₂ also closes the local circuit for the restoration of 30 switch S_{S2} via its own interrupter and the off-normal contact ONC₂. The brushes of the switch, therefore, return to normal and the switch cannot again be taken into use, before the supervisor has depressed key CK.

What is claimed is:

1. In an electrical signaling system, a variably operable first and second switch, two metallic wires between said switches, indicating means associated with the first switch, a plurality of mechanisms and a corresponding plurality of contact sets associated with the second switch, said mechanisms having a plurality of positions, cooperating contacts for each switch, a resistance for each contact set, a cold-cathode tube, means responsive to a change in the position of any of said contact sets to produce an electrical surge to ionize the cold-cathode tube, means for operating the second switch controlled by the tube, means for operating the first switch controlled by the second switch, and an actuating circuit for said indicating means controlled by said contact sets over said wires and the cooperating contacts of said switches.

55 2. An electrical signaling system according to claim 1, characterized in that one end of each resistance is connected to its associated contacts set, and a multiple connection from the other end of all said resistances to the primary winding of said transformer.

3. An electrical signaling system according to claim 1, a source of potential, means for applying a predetermined biasing potential to the control electrode of the cold-cathode tube in series with 65 the secondary winding of said transformer, the biasing potential being lower than the value of the control gap breakdown voltage of the tube.

4. In an electrical signaling system, a central and a distant point, two metallic wires between 70 said points, indicating means at the central point, a plurality of variably operable contact sets at the distant point, a switch at the central point having cooperating contacts, a switch at the distant point having cooperating contacts, a resistance for each contact set at the distant point, a

cold-cathode tube at the distant point, means responsive to a change in the position of any contact set to produce an electrical surge to ionize the cold-cathode tube, means for starting the switch at the distant point controlled by the tube, means for starting the second switch at the central point controlled by the first switch, and an actuating circuit for the indicating means controlled by said contact sets over said wires and cooperating contacts of said switches.

5. The electrical signaling system according to claim 4 and in which the tube has an anode, two control electrodes, a main gap and a control gap, a source of biasing potential for one of said control electrodes, and means including a circuit operable when a contact set closes to produce an electrical surge of such a magnitude and direction as to cause the breakdown of the tube main gap, and to produce, when a contact set opens, a surge of such a magnitude and direction that it will, aided by the biasing potential, cause the breakdown of the tube control gap.

6. In an electrical signaling system, a central and a distant point, two metallic wires between said points, indicating means at the central point, a plurality of variably operable contact sets and a resistance connected with each set at the distant point, a switch at each of said points having cooperating brushes and terminals, automatic means for each switch to operate its brushes successively to engage all of its terminals, a transformer having primary and secondary windings, and a cold-cathode tube at the distant point, a path closed by any contact set including the resistance associated therewith to produce in the secondary winding of the transformer an electrical surge, a connection from said secondary winding to the cold-cathode tube to ionize it by said surge, means for starting the automatic operation of the switch at the distant point controlled by the tube, means for starting the automatic operation of the switch at the central point controlled by the other switch, and an actuating circuit for the indicating means controlled by the contact sets over said wires and the brushes and terminals of the two switches.

7. In an electrical signaling system, a central and a distant point, two metallic wires between

said points, indicating means at the central point, a plurality of variably operable contact sets located at the distant point, a variably operable switch at the central point, a first relay responsive to positive and a second relay responsive to negative impulses connected at the central point with said wires, a variably operable switch at the distant point, other relays at the distant point for applying positive or negative pulses to each wire 5 in a closed circuit, a cold-cathode tube at the distant point, means responsive to a change in the position of any contact set to produce an electrical surge to operate the cold-cathode tube, means responsive to the operation or non-operation of said tube variably to operate said other relays, means for operating the switch at the distant point controlled by the tube, means responsive to the operation of either the first or the second relay for causing the switch at the central point to perform one operation.

20 8. The signaling system according to claim 7, and circuits for said indicating means controlled by said first and second relays.

9. The system according to claim 7 and in 25 which each switch has a bank of terminals and a brush cooperating therewith, a connection from each contact set to a different terminal in the bank of the switch at the distant point, and circuits for the other relays controlled over the 30 last mentioned contact bank for determining whether a positive or negative pulse will be applied to a wire.

10. The system according to claim 7, and a 35 pair of mechanically interlocking relays at the central point, and circuits therefore jointly controlled by the first and second relays so that the receipt of a pulse of one polarity will cause the operation and blocking of the first interlocking relay, while the receipt of a pulse of the opposite 40 polarity will cause the operation of the second interlocking relay and the de-blocking of the first interlocking relay.

11. The system according to claim 1, a special 45 signal at the central point, a circuit for said special signal controlled by the first and the second relays, and a calling button at the distant point for controlling said first and second relays.

WILLY POULIART.
